B. F. Bee,

Steam-Boiler Feed-Water Apparatus.

No. 11,433.

Patented Aug. 1, 1854.

UNITED STATES PATENT OFFICE.

BENJAMIN F. BEE, OF HARWICH, MASSACHUSETTS.

FEED-WATER APPARATUS FOR STEAM-BOILERS.

Specification of Letters Patent No. 11,438, dated August 1, 1854.

To all whom it may concern:

Be it known that I, BENJAMIN F. BEE, of Harwich, in the county of Barnstable and State of Massachusetts, have invented a new and Improved Apparatus or Machine for Supplying Steam-Boilers with Water, to which I have given the title of "Hydrotant"; and I do hereby declare that the following is a full, clear, and exact description of the construction and operation of the same, reference being had to the annexed drawings, making a part of this specification, in which—

Figure 1 is a plan view; Fig. 2, a front elevation; Fig. 3, an end elevation; Fig. 4, a front elevation of the table or slide upon which Fig. 2, is bolted.

A represents the outer surface of the boiler to which the machine is to be affixed.

B is the bed piece of the machine, bolted upon the above named surface, with an oblong, vertical, opening, communicating with the boiler and the space *a*, in which the steam valve C stands, and through the port *c*, with the space contained within the chest of the hydrotant. *b b* are flanges upon either side of this bed, which are embraced by angular flanges *d d*, extending from the table.

T is the table, sliding vertically upon the bed, being held in steam tight contact with the same by the set screw *e e e*.

E is the chest, bolted upon the table containing the valves, stem, connections, &c.

D is the water valve, lying horizontally with its ports communicating respectively with the top, and bottom, of the air chamber.

F is a vertical section of the air chamber, pipes, &c.

G is the valve stem.

H is the fingers, or clutch, which being pinned upon the stem, transmits its motion to the valves C, D, by the projections *i i i*, intruding into the spaces cast in the valves.

I is a rocking shaft, to which a reciprocating, intermittent, motion being given by suitable connection with some prime mover, the like motion is communicated by means of the lever K, to the valve stem, valves, &c.

The construction of the machine being sufficiently apparent from the foregoing reference, and description of parts, to enable any person skilled in mechanics to produce

the same, I will proceed to describe the principles and practice, of its operation. 55

The machine being confined substantially upon the boiler, at a proper height in reference to the water line, (this being shown in Fig. 3, L being the water line, or level, at which the present hydrotant might be supposed to retain the water, in a boiler of one horsepower,) the pipe P being duly connected with the tank or reservoir; which may be placed at any height above the level of the air chamber; water will flow into the air chamber, and compress the air contained therein, and stand at about *c*. Suppose now the rocking shaft, lever, stem, valves, &c., be in the position represented in the drawings. There will then be free communication between the boiler, and chest of the hydrotant, for the "to and fro" passage of water and steam; and as the water valve D is closed and held tight upon its seat by the pressure of the steam, no steam can escape 70 from the chest into the air chamber, or water pass from the chamber into the chest. It is plain that an equilibrium of steam and water will immediately take place in the boiler and chest, and if previous circumstances had caused the water to stand at L in the boiler, the same level will continue through the passages and parts of the hydrotant. At the next change of the shaft, lever, &c., the state of the valves will be reversed. The steam valve C, will close the port *c*, and exclude all communication between the boiler and chest. The same motion causes the valve D, to open the ports leading to the air chamber. It will be seen 75 by an inspection of the drawings that the port *m*, Fig. 2, is continued upward above the probable height of the water in air chamber; also that the port *n*, is continued downward by its coincidence with the space *o*, in valve D. Now whatever steam the chest contained at the instant of change in valves, will naturally seek the highest outlet, *i e*, the port *m*; and mingle with the air at the top of the chamber. The water on the contrary will seek the lowest course, through the port *n*, and having no counteracting influence, will completely fill the chest. The next change closes the water ports and opens the passage to the boiler when we shall find 80 the water in the chest, as much higher than 85

- in the boiler, as the upper surface of the chest, is above the water line. This surplus will immediately pass into the boiler, in its endeavor to seek an equilibrium. The space 5 it occupied will be filled with steam;—at the next change this steam will be replaced by water from the tank, and so on. Now if the consumption of water in the boiler be suspended, and the interchange of the valves 10 be continued; the quantity of water introduced at each feed will lessen continually, until the level of the water in boiler, arrives at the upper surface of the chest, when it will be nothing, and the supply will cease. 15 And "vice versa," should the consumption of water be disproportionately great, the supply will continue to augment, until the entire content of the chest is delivered at each feed; which content is calculated to 20 be such as amply to defray all reasonable expenditures, and leave a surplus for exigencies.

Thus far we have considered the operation of the hydrotant as maintaining the 25 height of the water at a particular point; but it is not infrequently the case that for various reasons, we may wish to vary this height. To effect this the table T, is made movable upon the bed piece B. A few turns 30 of the screw S, causes this table to rise or fall according to the direction, thus causing the chest with all its attachments to rise or fall, thus varying within certain limits the height at which the water will be sustained.

35 In ordinary cases where the pipe leading from the reservoir to the chamber is of sufficient length, its flexibility will accommodate this rise and fall; when this flexibility is wanting, the pipe P, is rendered smooth and 40 true, and surrounded with the box and packing p, through which it may move watertight.

Experience has shown that the rocking 45 shaft, and consequently the valves, should make about twenty double changes or strokes per minute; and as small a portion of the time as possible, should be consumed in making these changes, that the water may have the more time in which to perform its 50 evolutions.

By the compression of the air in the air chamber (F) as specified, much unnecessary friction is taken off from the slide valve (D), by reason of the counteracting pressure, on a portion of its area, (when the valve is closed against the admission of water) to the steam in the chest (E) acting upon the opposite side of the valve; but the greatest importance of the compressed air 55 and water vessel (F) is that, in connection with the steam being admitted by pipe uninterrupted and clear through and above the water therein when the valve (D) opens to pass water to the chest (E), an immediate 60 and forcible discharge of water takes place

into the chest and a sufficiency of supply is insured therein however rapidly the valve may be run, by reason of the compressed air above the water in the vessel (F) assisting the discharge in addition to the force of the steam acting on the water. This immediate and certain supply would not be insured were the steam to be allowed to find its way through the water itself or were the discharge of the water solely dependent upon the pressure of steam above the water in the supply vessel (F), as some time must necessarily elapse before the steam finds its way above the water in the supply vessel (F) and before the steam in the valve chest (E) and in the space above the water in the supply vessel (F) arrive at the same elastic force or pressure, to permit of the water being passed into the chest, by reason of the cooling effect on the steam which the water in the supply vessel (F) exerts as compared with the temperature and elastic force or pressure of the steam in the valve chest (E). The constant supply of compressed air which is maintained in the supply vessel F, it is 90 obvious, quickens the escape of water into the chest and neutralizes the tardiness naturally consequent upon the flow of the steam into the supply vessel (F) above the water and the difference of pressure of the steam 95 which, for a time, must unavoidably exist in the supply vessel (F) and valve chest (E).

I do not claim of themselves, as new in boiler feeders, a water chest and slide valve 100 operating in connection with a water supply vessel and arranged so as to be self regulating in keeping up a proper level of water in the boiler; nor yet do I claim as new, causing the steam from the boiler to act, by pipe 105 conveying it thereto, upon the surface of the water in the supply vessel to facilitate the discharge of water therefrom to the boiler. But

I do claim as new and useful and desire to 110 secure by Letters Patent—

1. The arrangement herein specified of the double slide valve (C and D) water chest (E) and steam and water passages (m n o and c) with the water supply vessel (F) 115 when the said supply vessel is made to form a compressed air receptacle by the immersion of the supply pipe (P) below the top surface of the water therein, or the compression of the air in the supply vessel being otherwise equivalently produced, and so that, a strong atmospheric pressure is brought to bear upon the surface of the water to serve, conjointly with the steam passing from the water chest through pipe into the compressed air receptacle, to establish that necessary equilibrium of pressure above and below the water in the supply vessel to produce a flow, and whereby the effect by condensation or cooling of the steam entering the 120 125 130

supply vessel is neutralized and a more immediate and certain discharge of water into the chest insured, as herein set forth; the whole being constructed and operating substantially is specified.

2. And I further claim the method herein described of varying the height at which the

water will be sustained, by raising and lowering the chest (E) and its attachments.

BENJAMIN F. BEE.
